UNITED STATES PATENT OFFICE.

FREDERICK A. PRESTON, OF HIGHLAND PARK, AND PHILIP W. MOORE, OF EVANSTON, ILLINOIS, ASSIGNEES TO THE P. & M. CO., OF CHICAGO, ILLINOIS, A CORPORATION OF ILLINOIS.

RAIL-STAY.

1,111,860.

Specification of Letters Patent. Patented Sept. 29, 1914.

Application filed May 2, 1914. Serial No. 835,906.

To all whom it may concern:

Be it known that we, FREDERICK A. PRESTON and PHILIP W. MOORE, citizens of the United States, residing at Highland Park, 5 in the county of Lake and State of Illinois, and Evanston, in the county of Cook and State of Illinois, respectively, have invented certain new and useful Improvements in Rail-Stays, of which the following is a specification.

Our invention relates to rail stays or rail anchors, that is, devices for preventing the longitudinal creep of railroad rails, and the object of the invention is to provide a 15 simple, economical device of this sort which can be readily applied to the rail and which, when in operative position, will take a hold on the rail that will not be loosened by vibration, by unequal expansion and contraction as between the rail and the device due to temperature changes, by a reverse longitudinal movement of the rail, or by other causes of like character having a tendency to destroy the effectiveness of the grip of 20 rail anchors on the rails which they engage.

The invention has for further objects such other new and improved arrangements, devices, and constructions relating to rail stays as will be hereinafter described and claimed.

The invention is illustrated, in certain preferred embodiments, in the accompanying drawings wherein—

Figure 1 is a side view of a rail anchor embodying one operative form of the invention, the anchor being shown as applied to a rail which is illustrated in cross section; Fig. 2, a sectional view taken on line 2—2 of Fig. 1; Fig. 3, a view, in perspective, of the yoke member of the anchor shown in the previous two figures; Fig. 4, a similar view of the yoke member of a modified form of the invention, and Fig. 5, a view, similar to Fig. 1, showing the application of the modified form of anchor to a railroad rail.

Like characters of reference designate like parts in the several figures of the drawings.

In the drawings, A designates a railroad rail and B one of the cross ties on which the rail is laid.

Referring to Figs. 1 to 3 inclusive, the anchor therein shown consists of a strap or

yoke C and a tie abutting element D having a tongue E which intervenes between the yoke C and the rail A. The yoke is preferably relatively rigid although it may have some little elasticity if desired. It bears, as shown, on opposite edges of the rail base, one extremity being preferably formed so as to provide a shoulder F which, when the device is in operative position on the rail, bears on the outer edge of the base flange so as to prevent the displacement of the yoke. The tongue E of the other member preferably has its extremity G turned up so that it bears against the under side of the base flange of the rail, the other end of the tongue being formed with a bend H which also bears against the under surface of the rail. The tongue is resilient and is designed to be put under considerable strain by the yoke.

The device is adjusted to the rail in the following manner: The tie abutting member D is placed under the rail against tie B. The extremity J of the yoke member is thrust under the rail and under the tongue E until it takes the position shown in the dotted lines in Fig. 1, that is, with the extremity L overlapping the base flange of the rail, substantially as far as possible. The extremity J of the yoke is then raised and the yoke thrust back crosswise of the rail in the other direction until the shoulder F rides over the edge of the base flanges; this, the operative position of the yoke, being shown in the full lines in Fig. 1. These transverse movements of the yoke, horizontal and vertical, compress the tongue E bending it from the dotted line position of Fig. 2 to the full line position of that figure. In order to facilitate the manipulation of the yoke the extremity J thereof is formed with recesses M adapted to receive the claw of a claw bar N or similar tool. The leverage afforded by the use of a tool of this sort will materially facilitate the work of bending the heavy spring E which must be bent before the yoke can be moved to its operative position. If desired the extremity J of the yoke may be formed with a cam surface O which, by bearing upon the edge of the rail base, will make the adjustment of the yoke easier. With the yoke provided with

recesses for a claw bar the cam face might be omitted.

The anchor shown in Figs. 4 and 5 is like the anchor shown in the preceding figures except that the yoke C' in this modification is not formed with the recesses for the claw bar and as it therefore has to be manipulated by hand or by means of a crow bar placed under it, the cam face O' is given a greater slant. The dotted lines in Fig. 5 show the first position of the yoke on the rail. The final operative position is indicated by the full lines.

While we have described our invention in certain preferred embodiments it will be understood that certain changes in the form and construction of the parts of the anchor might be devised without departure from the invention. Therefore we do not wish to be understood as limiting the invention to the particular constructions shown except so far as the same are specified in certain claims herein.

We claim:

- 25 1. A rail anchor comprising two elements one of which is resilient and is interposed between the rail and the other element so as to be put under strain by the other element against the rail and one of which is formed with means for giving said device a stationary position in the roadbed against its tendency to creep with the creep of the rail, one of said elements consisting of a yoke adapted to extend around the base of the rail and the other element being interposed between the yoke and the rail; said elements being capable of adjustment to said operative position by a movement of one of them transversely of the rail.
- 40 2. A rail anchor comprising two elements one of which is resilient and is interposed between the rail and the other element so as to be put under strain by the other element against the rail and one of which is formed with means for giving said device a stationary position in the roadbed against its tendency to creep with the creep of the rail, one of said elements consisting of a yoke adapted to extend around the base of the rail and the other element being interposed between the yoke and the rail; said elements being capable of adjustment to said operative position by the movement of the yoke transversely of the rail.
- 45 3. A rail anchor comprising two elements one of which is resilient so as to be put under strain by the other element and one of which is formed with means for giving said device a stationary position in the roadbed against its tendency to creep with the creep of the rail, one of said elements consisting of a yoke adapted to extend around the base of the rail and the other element being interposed between the yoke and the rail; said elements being capable of adjustment to said

operative position by the movement of the yoke transversely of the rail, said yoke being provided with lugs adapted to be engaged by a tool.

4. A rail anchor comprising two elements 70 one of which is resilient so as to be put under strain by the other element and one of which is formed with means for giving said device a stationary position in the road-bed against its tendency to creep with the creep 75 of the rail, one of said elements consisting of a yoke adapted to extend around the base of the rail and the other element being interposed between the yoke and the rail; said elements being capable of adjustment to said operative position by the movement of the yoke transversely of the rail, the latter being formed with a recess adapted to be engaged with a tool for this purpose.

5. A rail anchor comprising two elements 80 one of which is resilient so as to be put under strain by the other element and one of which is formed with means for giving said device a stationary position in the road-bed against its tendency to creep with the creep 85 of the rail, one of said elements consisting of a yoke adapted to extend around the base of the rail and the other element being interposed between the yoke and the rail; said elements being capable of adjustment to said operative position by the movement of the yoke transversely of the rail, the latter being formed with a recess adapted to be engaged with a tool for this purpose.

6. A rail anchor comprising two elements 90 one of which is resilient so as to be put under strain by the other element and one of which is formed with means for giving said device a stationary position in the road-bed 95 against its tendency to creep with the creep of the rail, one of said elements consisting of a yoke adapted to extend around the base of the rail and the other element being interposed between the yoke and the rail, said elements being capable of adjustment to said operative position by the movement of the yoke transversely of the rail, the latter being provided on opposite sides with recesses adapted to be engaged by a claw bar for this purpose.

10 6. A rail anchor comprising two elements one of which is resilient so as to be put under strain by the other element and one of which is formed with means for giving said device a stationary position in the road-bed 10 against its tendency to creep with the creep of the rail, one of said elements consisting of a yoke adapted to extend around the base of the rail and the other element being interposed between the yoke and the rail, said elements being capable of adjustment to said operative position by the movement of the yoke transversely of the rail, one extremity of the yoke having a cam surface adapted to engage the edge of the rail base during the 11 process of adjustment.

7. A rail anchor comprising two elements one of which is resilient so as to be put under strain by the other element and one of which is formed with means for giving said device a stationary position in the road-bed 12 against its tendency to creep with the creep of the rail, one of said elements consisting of a yoke adapted to extend around the base of the rail and the other element being interposed between the yoke and the rail; said elements being capable of adjustment to said operative position by the movement of the yoke transversely of the rail, said yoke being provided with lugs adapted to be en- 13

gaged by a tool and with a cam surface adapted to bear against the edge of the rail base during the process of adjustment.

8. A rail anchor comprising a tie abutting member formed with an elastic tongue adapted to bear at its extremity against the rail, and a yoke which extends around said rail base and tongue which in operative position puts said tongue under strain, said 10 yoke being adjustable to said position by a movement transversely of the rail.

9. A rail anchor comprising a tie abutting member formed with an elastic tongue adapted to bear at its extremity against the rail, and a yoke which extends around said rail base and tongue which in operative position puts said tongue under strain, said 15 yoke being adjustable to said position by a movement transversely of the rail and being 20 formed with a recess for the application thereto of a lever.

10. A rail anchor comprising a tie abutting member formed with an elastic tongue adapted to bear at its extremity against the rail, and a yoke which extends around said rail base and tongue which in operative position puts said tongue under strain, said 25 yoke being adjustable to said position by a movement transversely of the rail, and being 30 formed at one extremity with a cam surface which bears against the edge of the rail base during the process of adjustment.

11. A rail anchor comprising a tie abutting member formed with an elastic tongue 35 adapted to bear at both extremities against the under surface of the rail base being spaced therefrom between said points, and a yoke which extends around said rail base and tongue which, in operative position, 40 puts said tongue under strain, said yoke being adjustable to said position by a movement transversely of the rail.

12. A rail anchor comprising a tie abutting member provided with a resilient 45 tongue the outer extremity of which is bent so as to bear against the under surface of the rail and the inner extremity of which is formed with a bend connecting said tongue with said tie abutting member and bearing 50 against the under surface of the rail, and a yoke which is adapted to extend around said rail base and tongue and which, in the operative position of the parts, bends said tongue toward said rail base.

55 13. A rail anchor comprising co-acting rail engaging elements one of which is elastic and is interposed and under strain between another of said elements and the rail when the device is in operative position, said elements being adjusted to said position by a 60 movement of one of them toward the rail, and one element being formed with means for giving the device a stationary position in the road-bed as against the forward creeping tendency of the rail.

14. A rail anchor comprising co-acting rail engaging elements one of which is elastic and is interposed and under strain between another of said elements and the rail when the device is in operative position, one 70 of said elements being formed with a cam surface which engages with said rail when the device is being adjusted to said operative position, and one of said elements being formed with means for giving said device 75 a fixed position in the road-bed as against the forward creeping tendency of the rail.

15. A rail anchor comprising co-acting rail engaging elements one of which is elastic and is under strain when the device is 80 in operative position, one of said elements being provided with means engageable by tool whereby said device may be adjusted to said operative position, and one of said 85 elements being provided with means for giving the device a stationary position in the road-bed as against the forward creeping tendency of the rail.

16. A rail anchor comprising co-acting rail engaging elements one of which is elastic and is under strain when the device is in 90 operative position, one of said elements being formed with recesses engageable by a claw bar whereby the device may be adjusted to said operative position, and one 95 of said elements being provided with means for giving the device a stationary position in the road-bed as against the forward creeping tendency of the rail.

17. A rail anchor comprising co-acting rail engaging elements one of which provides a bowed spring arranged under the base of the rail, said device being adjustable to its operative position by a movement of the other element upwardly toward the rail, putting said bowed spring under strain, one 100 of said elements being provided with means for giving the device a stationary position in the road-bed, as against the forward 105 creeping tendency of the rail.

18. A rail anchor comprising co-acting rail engaging elements one of which provides a spring, said device being adjustable to its operative position by a movement 110 of the other element toward the rail putting said spring under strain between another of said elements and the rail, one of said elements being provided with means for giving the device a stationary position in the 115 road-bed as against the forward creeping tendency of the rail.

19. A rail anchor comprising co-acting rail engaging elements one of which provides a spring, said device being adjustable to its operative position by a movement of 120 the other element toward the rail putting said spring under strain, said other element being formed so as to be engageable by a tool for that purpose, one of said elements being provided with means for giving the 125 130

device a stationary position in the road-bed as against the forward creeping tendency of the rail.

20. A rail anchor comprising a tie abutting member formed with a bowed spring extending under the base of the rail, and a yoke adapted to embrace the base of the rail and said spring, said yoke being mov-

able upwardly toward the rail base and crosswise thereof to its operative position. 10
